UNITED STATES PATENT OFFICE.

JACOB KANTOR, OF PORT ELIZABETH, CAPE COLONY, SOUTH AFRICA.

PIANO WREST-PLANK.

1,212,775.

Specification of Letters Patent. Patented Jan. 16, 1917.

Application filed July 14, 1914. Serial No. 851,021.

To all whom it may concern:

Be it known that I, JACOB KANTOR, a citizen of Cape Colony, residing at Main street 57, Port Elizabeth, Cape Colony, South Africa, have invented certain new and useful Improvements in Piano Wrest-Planks, of which the following is a specification.

My invention relates to improvements in wrest planks for pianos and other musical instruments.

The object of the improvements is to provide a wrest plank in which the pegs are not liable to become loose by the board becoming dry, as is the case for example in tropical and dry climates even if the board consists of superposed layers of wood.

My invention consists in composing the board of layers of wood and fabric disposed between the layers of wood and glued thereto, the fabric being of such a nature as not to be subject to the influence of dry and wet weather. I have found that layers of rough linen bagging are best suited for the purpose, the pores of the bagging being filled 25 with the gluing material. The layers of bagging stick to the layers of wood in such a way as to prevent warping of the same. I have found that a wrest plank of this construction does not show widening of the peg 30 holes even after several years of use in the most dry climates, so that the pegs are rigidly held in their holes.

For the purpose of explaining the invention an example embodying the same has 35 been shown in the accompanying drawing, in which the same letters of reference have been used in all the views to indicate corresponding parts.

In said drawing—Figure 1, is a perspective view of a part of a wrest plank with several pegs or tuning pins in place, a short section of the plank being shown, and Fig. 2, is a partial section of the same taken through one of the tuning pins.

In the example shown in the drawing the wrest plank consists of four superposed layers *a*, *b*, *c*, *d* of wood, the top and bottom layers *a* and *d* being thinner than the medium layers *b* and *c*. The layers *a*, *c* and *d* 45 are composed of transverse boards which are displaced relatively to one another, while the layer *b* consists of a single continuous longitudinal board. Between all the layers

of wood there are layers *e* of bagging which are glued and fixed thereto while compressing the whole board.

The holes for the pegs *f* do not change under any conditions of the climate.

I claim herein as my invention:

1. A wrest plank for musical instruments 60 consisting of alternate layers of wood and woven fabric combined by gluing.

2. A wrest plank for musical instruments 65 consisting of alternate plane layers of wood and linen bagging combined by gluing.

3. A wrest plank for musical instruments comprising in combination four superposed layers of wood, the top and bottom layers being thinner than the intermediate layers, 70 layers of linen bagging disposed between said layers of wood and the whole combined by a gluing material.

4. The combination with a wrest plank 75 consisting of four superposed layers of wood, the top and bottom layers being thinner than the intermediate layers, layers of linen bagging disposed between said layers of wood and the whole combined by a gluing material, of a series of pegs inserted into said plank for the attachment of strings 80 thereto.

5. A wrest plank for musical instruments comprising in combination, four superposed layers of wood, the top and bottom layers being thinner than the intermediate layers, 85 one of the intermediate layers of wood having the grain running longitudinally of the wrest plank and the remaining layers of wood having their grain running transversely of the wrest plank, layers of textile 90 fabric disposed between said layers of wood, and the whole being held together by gluing material.

6. The combination with a wrest plank 95 consisting of four superposed layers of wood, the top and bottom layers being thinner than the intermediate layers, one of the intermediate layers of wood having its grain running longitudinally of the wrest plank and the remaining layers having their grain running transversely of the wrest 100 plank, layers of textile bagging interposed between said layers of wood, and the whole being held together by gluing material, of a series of pegs inserted into said plank for 105 the attachment of strings thereto.

7. The combination of a wrest plank for musical instruments consisting of alternate plane layers of wood and linen bagging combined by gluing, and a series of pegs inserted into said plank for the attachment of strings thereto.

In testimony whereof I affix my signature in presence of two witnesses.

JACOB KANTOR.

Witnesses:

M. E. WAKEFIELD,
WILFRED NICHOLSON.
